(57) **CLAIM**

The ornamental design for an electronic device, as shown and described.

DESCRIPTION

FIG. 1 is a front, perspective view of a first embodiment of an electronic device showing our new design;

FIG. 2 is rear, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an additional top view thereof, with the electronic device shown in an open position;

FIG. 10 is an additional top, front perspective view thereof, with the electronic device shown in an open position;

FIG. 11 is an additional bottom, rear perspective view thereof, with the electronic device shown in an open position; and,

FIG. 12 is an additional left side view thereof, with the electronic device shown in an open position.

The keys of the electronic device are black. The portion of the electronic device shown in gray shading represents a metallic-looking surface that preferably contrasts with the black portions. The broken line showing is for the purpose of illustrating environmental structure and forms no part of the claimed design.
